B. E. MAXWELL.

MACHINE FOR PULLING TREADS FROM TIRES AND FOR SEPARATING PLYS OF FABRIC.
FILED Nov. 18, 1920.

Patented Jan. 30, 1923.

1,443,495

UNITED STATES PATENT OFFICE.

BERT E. MAXWELL, OF WICHITA, KANSAS.

MACHINE FOR PULLING TREADS FROM TIRES AND FOR SEPARATING PLYS OF FABRIC.

Application filed November 18, 1920. Serial No. 424,933.

To all whom it may concern:

Be it known that I, BERT E. MAXWELL, a citizen of the United States, and resident of Wichita, in the county of Sedgwick and 5 State of Kansas, have invented a certain new and useful Machine for Pulling Treads from Tires and for Separating Plys of Fabric, of which the following is a specification.

10 My invention relates to a machine for pulling treads from tires and for separating plys of fabric, in order to use the de-treaded portions of the tires for "reliners" or other purposes. Heretofore this operation has been performed by hand, requiring 15 usually two men, one to hold the inner portion of the tire, the other to hold the tread portion, and pulling in opposite directions to tear the said parts of the tire apart.

20 My machine for this purpose is automatic, and requires only one attendant.

The preferred embodiment of the invention is shown in the accompanying drawings, in which—

25 Fig. 1 is a top plan view, omitting a brace 9, a portion of the pulley being broken away; Fig. 2 is an outer end elevation of the machine; Fig. 3 is a diagram to show the arrangement of the gearing through which the feed rollers are actuated; Fig. 4 is a diagram showing how a 30 cut tire is split in layers by the traction of the rollers; Fig. 5 is an enlarged detail view of any of the four adjustable journal boxes; Fig. 6 is a cross section of any one 35 of the four feed rollers.

Referring more in detail to the parts;

The frame comprises a horizontal U shaped frame 1, 5, 2, of which the arms 1, 40 2 are parallel and integral with an inner end of pedestal 5. Pedestal 5 is integral with an annular bracket consisting of a vertical plate 3 and a horizontal plate 4. Both plates 3, 4 are secured by screws to a bench, 45 and the machine overhangs to afford space for the tires operated on to hang therefrom.

The inner pedestal 5 supports a standard

6. A similar post 7 is either integral with plate 4 or is bolted to the bench at 8. A horizontal bar 9 is secured to the tops of posts 50 6, 7 and connects them as a brace, passing over the pulley 10.

The frame further comprises two horizontal tie-bars 12, 13. One end of each tie-bar is secured to an end of inner pedestal 5

by two cap screws 14. The outer end of one tie-bar 12 is rigidly secured a pedestal 15—16. To the outer end of the other tie-bar 13 is rigidly secured a pedestal 17—18. The inner ends of said pedestals are spaced 60 apart, as shown in Fig. 2, to form a gap for the insertion of an uncut tire at the outer end of the machine.

The frame further comprises at the outer end of the machine a lower connecting bar 19 and an upper connecting bar 20, and a movable pedestal 21. The upper connecting bar 20 is pivoted on a pin 22 held by a lug 23 on pedestal 15—16. In this bar 20 are two vertical slots, one to receive the 70 upper end of the movable pedestal 21 which is located between the two fixed pedestals, and the other to receive an upstanding lug 24 on the inner end of pedestal 17—18. The lower connecting bar 19 is pivoted to the 75 outer end of tie-bar 13, on a pin 25. In this connecting bar are two vertical slots, to receive two depending lugs 26, 27, the former being a part of connecting bar 12, the latter a part of movable pedestal 21.

80 When pins 28, 29, 30, 31' are inserted in holes through the connecting bars and through the lugs which enter the aforesaid slots, the free ends of the connecting bars are rigidly supported, and the movable pedestal 21 is also rigidly supported, all as shown on Fig. 2. The said pins are loose enough in the holes to be easily removable.

Outer journal-blocks 31, 32 are slidable 90 in slots in the upper parts of pedestals 15, 17. In these blocks are gudgeons 33, 34 of two rollers 35, 36. Shafts 37, 38 on the opposite ends of said rollers are journaled in blocks 31, 32, which are slidable in slots in the inner pedestal 5, which is integral.

95 Movements of the outer journal blocks 31, 32 are effected by hand-wheels 39—40 on screws 41, 42 threaded through the pedestals. Corresponding movements of the inner journal-blocks of rollers 35, 36 are effected by hand-wheels 43, 44 on screws 45, 46 threaded through pedestal 5.

The details of each of the four journal-blocks are shown by Fig. 5, in which 47 indicates a collar fastened in the screw 41 by a pin 48, the end of the screw abuts on spring cap 49 which fits into a short helical spring 50 seated in a recess in the blocks 31. The slot 51 permits movement of the block toward and upon the screw when the 110

roller journalled in the hole 52 is forced in direction of arrow.

Keyed on the inner end shaft of roller 35 is a double staggered gear 53, having large teeth like those of wringer gears. A similar double gear 55, keyed on the inner shaft 38 of roller 36.

Referring now to Fig. 2:—the movable pedestal 21 has a bearing for gudgeon 54 of a roller 56, a companion to roller 35. The other arbor or end shaft 56' of roller 56 is of course journalled in pedestal 5, and is extended to receive a spur-gear 57 in addition to a double staggered gear 58 meshing the gear 53 of roller 35.

The fourth roller 59 a companion to roller 36, has its gudgeon 60 journalled in the inner end of pedestal 18, and its inner end shaft 59 journalled in pedestal 5 and extended to carry a double staggered gear 61 and a spur gear 62, the latter of the same diameter as spur gear 57 and meshing therewith. Also keyed on shaft 59' is a large spur gear 63. A shaft 64 journalled in posts 6, 7, carries a drive pinion 66, a clutch 67, 68, and a loose pulley. Pinion 66 meshes with gear 63. Clutch member 67 is pinned on the shaft, while clutch member 68 is a part of the hub of the pulley, which is longitudinally slideable. Motion for throwing the clutch is imparted through a lever 69, fulcrumed at 70 on a fixed lug 71, and having a pivot connection 72 with any suitable device for shifting the hub of the pulley to close and open the clutch.

All parts of the machine but the feed rollers have now been described.

Each of said rollers has cut or cast there-in a large number of circumferential grooves 73. The lands 74 between the grooves are each corrugated as indicated by lines 76 on Fig. 1; the corrugations being longitudinal to the roller or transverse to the lands. The rollers of each pair are so set that the lands of each register with the grooves of the other roller. The outside rollers 35, 36 are of course pressed against the companion rollers when the hand screws are turned up sufficiently to partly compress the springs.

Operations.—To start the operation on an uncut, (endless) tire. I first cut the base beads from the tire. Next I make transverse incision through the tread only, or, in some cases, through the tread and one layer of fabric also; then peel off one end of the tread (or tread and fabric) to a length of about four inches or more, I next remove pins 28, 29, turn back the bar 20 on its pivot 22, thus freeing the upper end of pedestal 21; remove pins 30, 31' and pull down bar 19 on its pivot 25, thus freeing the lower end of pedestal 21. There is thus formed an aperture on each side of said pedestal.

The pressure upon the outer rollers is relaxed by turning the hand-wheels reversely,

and further turning draws the outer roller 35, 36 away from the inner rollers.

The tire is flattened at one point and is inserted through one gap and between rollers 35, 36; also inserted through the gap at the right of pedestal 21. Bars 19, 20 are then replaced and fastened by their pins. The tire is now disposed like the part *a* on Fig. 4. The flap of the tread is now inserted between rollers 59, 36 like the part *b*. The rollers 75 are then tensioned up by turning up the hand-wheels.

Pulley 10 being driven in the direction of the arrow on Fig. 3 the clutch is closed. The pair of rollers 35, 56 pull the inner portion 80 of the tire down between them, while the pair of rollers 59, 36 pull the outer portion of the tire down between them at the same rate of motion. The corrugations grip the parts so that slipping is impossible and the 85 outer and inner parts of the tire are thus torn apart.

The inner portion is then available as a liner for tires.

In some cases I cut the tire clear through 90 before splitting it. This makes it unnecessary to open up the machine in the manner above described, as the separated ends of the inner and outer layers can be inserted between the feed-rollers from above. 95

The double staggered gearing remains in mesh at all times while the machine is in operation, even when the rollers are forced outward by the thicker portions of a tire tread or the inside layers. 100

It is not deemed necessary to show on the drawings oil holes or oil cups for journal lubrication.

Having thus described my invention, what I claim and desire to secure by Letters Patent, is—

1. In a tire splitting machine, a supporting frame, pedestal bearings in said frame for the end shafts and gudgeons of four feeding rollers arranged on coacting pairs, 110 one end of the frame being formed with two apertures adapted to permit the insertion of an endless tire between the pairs of rollers and between the rollers of one pair; and means for simultaneously driving both 115 pairs of rollers through the medium of a spur gear wheel on the shaft of one of the rollers.

2. In a tire splitting machine, a supporting frame, pedestal bearings in said frame 120 for the end shafts and gudgeons of four feeding rollers arranged in coacting pairs, one end of the frame being formed with two apertures adapted to permit the insertion of an endless tire between the pairs of 125 rollers and between the rollers of one pair; movable frame members normally barring said apertures in order to support one of the bearings, fastening pins for said movable frame members, and means for simul- 130

aneously driving both pairs of rollers through the medium of a spur gear wheel on the shaft of one of the rollers.

3. In a tire splitting machine, a supporting frame comprising pedestal bearings; two pairs of feeding rollers journaled in said bearings, one end of the frame comprising outside pedestals 15—16 and 17—18; an arm 20, pivoted on one of said pedestals 10 and having two slots therein, an arm 19 pivoted on the other pedestal and having two slots therein, fastening lugs 24 and 26 on said pedestals, an intermediate bearing-piece 21 supported in slots in said arms 19, 20, and fastening pins passed through registered holes in said arms, lugs and ends of piece 21, for bracing said pedestals and supporting said bearing-piece 21.

4. In a tire splitting machine, a feeding roller having a plurality of narrow grooves 20 cut circumferentially therein, and the lands between said grooves being corrugated for gripping a strip or ring of combined rubber and fabric in coaction with a similar roller. 25

5. In a tire splitting machine, a pair of coacting feeding rollers, each roller having a series of annular grooves cut therein, the lands between said grooves being corrugated transversely, and the rollers being adjusted 30 with the lands of each registered with the grooves of the other.

BERT E. MAXWELL.
